The ornamental design for a thermos bottle, as shown and described.

DESCRIPTION

FIG. 1 is a perspective view of a thermos bottle showing my new design;

FIG. 2 is a front view thereof, the opposite rear view being mirror image thereof;

FIG. 3 is a top plan view thereof;

FIG. 4 is a bottom view thereof;

FIG. 5 is a left side elevation thereof;

FIG. 6 is a right side elevation thereof;

FIG. 7 is a perspective view of a cover portion with a cap removed thereof;

FIG. 8 is a front view of a cover portion with a cap removed thereof;

FIG. 9 is a rearview of a cover portion with a cap removed thereof;

FIG. 10 is a top plan view of a cover portion with a cap removed thereof;

FIG. 11 is a bottom plan view of a cover portion with a cap removed thereof;

FIG. 12 is a left side elevation view of a cover portion with a cap removed thereof;

FIG. 13 is a right side elevation of a cover portion with a cap removed thereof; and,

FIG. 14 is a perspective view of a thermos bottle with the cap on and shown in a used condition.

The portions of the thermos bottle shown in broken lines form no part of the claimed design.
